UNITED STATES PATENT OFFICE.

JOHN M. McMURTRIE AND ISAIAH ROBERTON, OF GLASGOW, SCOTLAND.

HYDROCARBON-BURNER.

1,077,848.

Specification of Letters Patent.

Patented Nov. 4, 1913.

Application filed March 22, 1912. Serial No. 685,559.

To all whom it may concern:

Be it known that we, JOHN McLEOWNAN McMURTRIE and ISAIAH ROBERTON, both subjects of the King of Great Britain and Ireland, and residents, respectively, of 212 5 West Regent street, Glasgow, Scotland, and 25 St. Andrews Drive, Pollokshields, Glasgow, Scotland, have invented new and useful Improvements in Hydrocarbon-Burners, 10 of which the following is a specification:

This invention has reference to improvements in hydro-carbon burners or appliances for heating and lighting purposes of the class in which a steam jet is fitted 15 concentrically within, and an air jet is fitted concentrically without, an oil jet and consists in the arrangement and construction of a series or a number of burners in a frame which is formed with two passages 20 or ducts through one of which steam or other suitable fluid is conveyed to the ejector jets and through the other oil is conveyed to the oil jets of the burners which are formed with orifices or ports for the 25 admission of air.

In order that our said invention and the manner of carrying same into effect or practice may be properly understood we have hereunto appended three sheets of explanatory drawings in which—

Figure 1 is an elevation of a hydro-carbon burner or appliance for heating and lighting purposes as constructed according to our improvements and Fig. 2 is a sectional plan view of same; the section being taken on the line 2—2 of Fig. 1; and Fig. 3 is a sectional elevation at right angles to Fig. 1; the section being taken on the line 3—3 of Fig. 2.

Referring to these drawings:—In carrying these improvements into practice as applied to a steam boiler or like furnace we construct a frame 1 into which we lead a pipe 2 fitted with a regulating valve or cock 40 (not shown) through which would be fed, by the suction action of the jets which will be hereinafter more particularly referred to, a suitable oil or hydrocarbon which would flow into a duct or receiver 3 common to a series of burners 4. A similar pipe 5 fitted with a valve, (not shown) would lead high pressure steam, from a boiler or other source of supply, or it may be heated air, gas or other suitable fluid or a combination of 45 these, to a similar duct or receiver 6 in the frame 1 common to the series of burners 4.

Each burner 4 of the series has an oil or fluid cup or like chamber 7 controlled by a valve 8 which is fed from the oil duct 3 in the frame 1 common to all; and the steam or other highly heated fluid passes from the duct 6 common to all through a valve 9 to a trapping chamber 10, which is preferably fitted with overhung tube 18 so as to trap any deposits which are removed through a removable plug 11. The steam or fluid supply in passing from the duct 6 to the trapping chamber 10 passes through a coil of piping 12 on which the flame from the burner 4 impinges so as to superheat 70 same to a temperature of say about 1000 degrees Fahrenheit.

From the trapping chamber 10 the superheated steam or fluid passes to a central nozzle or steam jet 13 which acts as an injector or ejector and draws the oil or hydrocarbon from its annular chamber 7 surrounding said central nozzle 13 through an annular aperture 14 in a thin stream into a nozzle or oil jet 15 leading into a passage or air jet 17 formed in a cap or burner 4. A series of ducts 19 are formed in the cap 4 so that atmospheric air will be drawn into the passage 17 by the vapor mixture issuing from the jet 15.

The jet 15 extends some distance into the passage 17 and the jet 13 some distance into the jet 15 in order that the air will be drawn in through the ducts 19 and the oil from the storage tank situated below the level 90 of the apparatus into the jet 15 through the chamber 7.

The introduction of the air into the passage 17 (Fig. 3) near the issuing vapor mixture enables the flame to burn from near the mouth of the jet. By this arrangement all or any number of burners may be used or isolated to suit the heat requirements of the furnace.

The frame 1 may be fitted with a cover 100 or casing 16 fitted with a hinged or removable door or doors for access to the appliances.

What we claim as our invention and desire to secure by Letters Patent, is:—

1. A burner consisting of a nozzle having an air passage leading thereto; a second nozzle of smaller diameter than and extending into the first nozzle, said second nozzle forming a closure for the bottom of the first nozzle and having an oil passage 110 leading into its inner end; a third nozzle

having a portion of smaller diameter than and leading part way into the second nozzle; a cap surrounding the lower portion of the third nozzle and forming a trap 5 therefor; with a steam conduit communicating with the trap.

2. A burner consisting of a nozzle having an air passage leading thereto; a second nozzle of smaller diameter than and extending into the first mentioned nozzle, said second nozzle forming a closure for the bottom of the first nozzle and having an oil passage leading into its inner end; a third nozzle having a portion of smaller 10 diameter than and leading part way into the second nozzle; a cap located directly below the lower portion of the third nozzle and forming a trap therefor; with a steam conduit communicating with the trap.
- 15 3. An appliance for heating and lighting 20

purposes consisting of a supporting frame having an oil duct and a steam duct; a plurality of burners supported by said frame and each including an oil nozzle, a steam nozzle and an air nozzle; with a plurality 25 of heating coils on said frame and each having one end in communication with the steam duct, said frame having a plurality of ducts respectively connecting the oil ducts with the oil nozzles and also having passages 30 respectively connecting the heating coils with the steam nozzles.

In testimony whereof, we have signed our names to this specification, in the presence of two subscribing witnesses.

JOHN M. McMURTRIE.
ISAIAH ROBERTON.
